(57) **CLAIM**

The ornamental design for a door opener lever, as shown and described.

DESCRIPTION

FIG. 1 is an isometric view of a door opener lever showing our new design;

FIG. 2 is an isometric view of FIG. 1; shown at a different angle;

FIG. 3 is a top view of FIG. 1;

FIG. 4 is a front view of FIG. 1;

FIG. 5 is a bottom view of FIG. 1;

FIG. 6 is a left side view of FIG. 1; and,

FIG. 7 is a right side view of FIG. 1.

The broken lines are for illustrative purposes only and form no part of the claimed design.
